SPENCER H. PHELPS, OF EVANSVILLE, INDIANA, ASSIGNOR OF ONE-HALF TO CHARLES F. SCHROEDER AND ONE-HALF TO LOUIS E. FRICKE, BOTH OF EVANSVILLE, INDIANA.

COLTER.

1,149,945.

Specification of Letters Patent. Patented Aug. 10, 1915.

Application filed February 10, 1915. Serial No. 7,306.

To all whom it may concern:

Be it known that I, SPENCER H. PHELPS, a citizen of the United States, and a resident of Evansville, in the county of Vanderburgh and State of Indiana, have invented a new and Improved Colter, of which the following is a full, clear, and exact description.

This invention relates to farm implements and more particularly to an improved colter.

The primary object of the invention is to provide a novel support for a revolving colter blade adapted for attachment to a plow beam so that the blade may be adjusted at the proper angle so as to be set vertically or at an angle with respect to the ground, or adjusted up and down according to the depth of the furrow to be cut, these adjustments being capable of accomplishment in a simple and effective manner.

With the above and other objects in view, the invention resides more particularly in the peculiar combination and arrangement of parts to be hereinafter more fully described, illustrated and claimed, it being also an object to provide a device which is simple in construction, durable and efficient in operation and not likely to get out of order.

Reference is to be had to the accompanying drawings forming a part of this specification, in which similar characters of reference indicate corresponding parts in all the views and in which—

Figure 1 is a side elevation of the improved colter applied to a plow beam, a fragmentary portion of the latter being shown; Fig. 2 is an enlarged vertical sectional view taken on the line 2—2 of Fig. 1; Fig. 3 is a plan view of the structure shown in Fig. 1 with the colter blade and its yoke omitted.

As illustrated, the device includes a beam plate 10 which is designed to fit one side of a plow beam 11 which may be of either steel or wood, of any width or thickness. The beam plate 10 is set at an angle and clamped to the beam by bolts 12 adjusted through the extremities thereof and a beam plate 13 on the opposite side of the beam, the beam plate 10 having a rosette face 14 against which is clamped a guide plate 15 having a corresponding face to lock into the face of the beam plate 10 and to be angularly ad-

justed thereon by the coaction of the teeth 55 and intervening notches of said plates.

The numeral 16 designates a standard which is slotted vertically, as shown at 17, to be engaged by a clamping bolt 18 which forms a swivel connection between the 60 plates 10 and 15 and the standard, the guide plate 15 having a convex face 19 between which and the standard a sliding block 20 is disposed. This block is provided with a concave face 21 opposing the convex face 19 65 and opposite pairs of vertically spaced horizontal guide lugs 22 project from the guide plate 15 to receive and guide the standard therebetween. A saddle washer 23 is fitted against the outer side of the standard with 70 flanges to overlie the sides thereof so that when the nuts of the bolt 18 are clamped tight the standard will be held from swinging on a horizontal axis due to the clamping engagement of the rosetted faces of the 75 plates 10 and 15.

At the lower end the standard 16 is apertured and above said aperture is provided with a segmental rosette or notched face 24, the aperture being designed to take a bolt 25 80 which pivotally supports a bracket 26. This bracket is provided with a segmental notched or rosetted face 27 coacting with the notches 24 above the pivot 25, and the lower end of the bracket has a portion 28 which extends 85 up in rear of the lower end of the standard. The bracket 26 is also provided with vertically spaced horizontal ears 36 between which a yoke 29, in which a rolling steel 90 colter blade 30 is journaled, is pivoted through the medium of a vertical bearing sleeve 31, and a bolt 32 passing through said sleeve and ears.

According to the construction described the standard can be shifted to the right or 95 left by loosening the bolt 18 and moving the block 20 up and down, it being understood that the plates 10 and 13 are set at the proper angle according to the width of the beam, are clamped together and then the 100 guide plate 15 adjusted to bring the standard at the proper angle when pivoted on the bolt 18 as a horizontal axis. Furthermore, the yoke 29 may be adjusted on the pivot 25 due to the coacting notched or rosetted faces 24 and 27 so that the colter blade can be kept plumb, as shown in dotted lines in Fig. 2, or set at any desired angle 105

according to the furrow to be cut. The advantage of this construction is that the colter blade can be set at any desired position with respect to the plow, allowing for any twisting or imperfect construction of the beam, while the slotting of the standard permits it to be adjusted vertically for raising and lowering the colter blade.

Having thus described my invention, what I claim as new and desire to secure by Letters Patent is:—

1. In a colter, a clamp, a standard mounted to be adjusted vertically and angularly on a horizontal axis with respect thereto and a colter blade pivoted to the standard to be adjusted on a horizontal axis.
2. In a colter construction, a clamp for attachment to a plow beam, a standard pivoted thereto for lateral angular adjustment and a colter blade having a yoke pivoted to the standard for lateral adjustment.
3. In a colter construction, a clamp for attachment to a plow beam, a standard pivoted thereto for lateral angular adjustment and a colter blade having a yoke pivoted to the standard for lateral swinging movement, said standard being adapted for vertical adjustment with respect to the clamp.
4. A colter adapted for attachment to plow beams or the like, comprising a beam plate having a rosette face, a second beam plate, clamping means connecting said plates, a guide plate having a rosette face coöperating with the rosette face of the first named beam plate and having a convex face portion and guide members, a standard vertically slotted, a clamping member forming a swivel connection between the first named beam plate, guide plate and the standard and engaging the slot of the latter whereby the standard may be vertically adjusted or swung on a horizontal pivot and held against movement, a block fitted between the convex face portion of the guide plate and the standard and having a concave face coöperating with said convex face whereby vertical adjustment of the block will swing the standard laterally with respect to the guide plate and beam, said standard having a segmental notched portion at right angles to the rosette faces of the plates aforesaid, a bracket pivoted to the standard and having a coacting notched face portion to be adjusted laterally with respect to the standard, a yoke swiveled in the bracket and a colter blade journaled in the yoke.

a yoke pivoted to the standard for adjustment at right angles to the direction of extent of the plow beam.

5. A colter adapted for attachment to plow beams or the like, comprising a beam plate having a rosette face, a second beam plate, clamping means connecting said plates, a guide plate having a rosette face coöperating with the rosette face of the first named beam plate and having a convex face portion and guide members, a standard vertically slotted, a clamping member forming a swivel connection between the first named beam plate, guide plate and the standard and engaging the slot of the latter whereby the standard may be vertically adjusted or swung on a horizontal pivot and held against movement, a block fitted between the convex face portion of the guide plate and the standard and having a concave face coöperating with said convex face whereby vertical adjustment of the block will swing the standard laterally with respect to the guide plate and beam, said standard having a segmental notched portion at right angles to the rosette faces of the plates aforesaid, a bracket pivoted to the standard and having a coacting notched face portion to be adjusted laterally with respect to the standard, a yoke swiveled in the bracket and a colter blade journaled in the yoke.

6. In a colter, a clamp, a standard vertically and angularly adjustably mounted on the clamp, and a pivoted colter carrying member laterally adjustable on the standard.

In testimony whereof I have signed my name to this specification in the presence of two subscribing witnesses.

SPENCER H. PHELPS.
